US0D1111348S

(12) United States Design Patent (10) Patent No.: US D1,111,348 S
(45) Date of Patent:  Feb. 10, 2026

(54) MULE

(71) Applicant: Birkenstock IP GmbH, Linz am Rhein (DE)

(72) Inventor: Arno Marchand, Linz am Rhein (DE)

(73) Assignee: Birkenstock IP GmbH, Linz am Rhein (DE)

() Term: 15 Years

(21) Appl. No.: 35/522,987

(22) Filed: Oct. 10, 2024

(80) Hague Agreement Data

Int. Filing Date: Oct. 10, 2024

Int. Reg. No.: DM/241738

Int. Reg. Date: Oct. 10, 2024

Int. Reg. Pub. Date: Nov. 15, 2024

(30) Foreign Application Priority Data

Apr. 11, 2024 (EM) 015057085-0001
Apr. 11, 2024 (EM) 015057085-0004

(51) LOC (15) Cl. 02-04

(52) U.S. Cl.

USPC D2/923; D2/957; D2/960

(58) Field of Classification Search
